Inventor
Edward B. Ekstrand,

By Clarence O'Brien
Attorney

UNITED STATES PATENT OFFICE

EDWARD BERGER EKSTRAND, OF WEST SOMERVILLE, MASSACHUSETTS

FUSE PLUG

Application filed September 16, 1929. Serial No. 392,850.

This invention relates broadly to devices for making connections to electric circuits, and has as its primary object to simplify the construction of fuse plugs.

5 The invention consists broadly in the provision of a plug formed of bakelite or similar composition, provided with a socket extending inwardly from one end thereof, and a pair of spring contact members imbedded within 10 said socket, one end of each of said spring contact members extending into the socket and being adapted for receiving and maintaining a fuse within the socket, one of said contact members constituting a spring contact 15 at the bottom end of the plug.

Another object of the invention is to provide a fuse plug which is simple in construction, compact, strong, durable, and wherein the fuse may be securely maintained and at 20 the same time permitting of a ready removal or replacement of the fuse.

Other objects and advantages of the invention will become apparent during a study of the following description, taken in connection with the accompanying drawings, wherein:

Figure 1 is a vertical transverse sectional view taken through a fuse plug constructed in accordance with the invention, the spring 30 contact members and fuse being shown in elevation.

Figure 2 is a top plan view of the assembled fuse plug.

Figure 3 is a detail elevational view of the 35 longer spring contact member.

With reference more in detail to the drawings, it will be seen that my improved fuse plug consists of a cylindrical body 5 formed of bakelite or any other suitable composition, 40 said plug being provided at one end with an outstanding peripheral flange 6. The body 5 is provided with a screw threaded sleeve 7, said sleeve being imbedded in the material as shown to advantage in Figure 1. The body 5 of the plug is also provided with a centrally disposed substantially circular socket or recess 8 extending inwardly from the top or flanged end of the body.

The socket 8 is of suitable diameter, and is 50 provided with diametrically opposed vertical

notches 9—9. A relatively short spring contact member 10 has the major portion thereof imbedded within the body 5, one end of the contact member 10 extending into the socket 8, said one end being bent backwardly upon 55 itself to provide an arcuate spring-like finger 11 adapted to be disposed in one of the notches 9.

As shown to advantage in Figure 1, the spring contact member 10 extends diagonally 60 through the body 5. A relatively larger spring contact member 12 is of somewhat U-shaped formation, and has its bight portion 13 disposed outwardly of the body 5 in spaced relation to that end of the body remote from the flange 6. The smaller leg 14 of the contact member 12 terminates in a laterally extended end portion and this end of the leg portion is imbedded within the body 5.

The larger leg 15 of the member 12 extends diagonally through the body 5 to terminate within the socket 8 in spaced parallelism with said one end of the member 10, and this end of the leg 15 terminates likewise in an arcuate-shaped spring finger 16, 70 which finger is formed by bending the material of the leg 15 backwardly upon itself as shown to advantage in Figure 1. The finger 16 rests in the other of the notches 9.

A conventional fuse 17 is adapted to be 80 positioned in the socket 8 and the fuse 17 has one end thereof received in a pocket 18 formed in that end of the spring contact member 10 arranged within the socket 8, said pocket 18 being formed by pressing the 85 material of the spring outwardly as is apparent from a study of Figures 1 and 3.

The opposite end of the fuse 17 is adapted to be received in a like pocket 19 formed in that end of the leg 15 which is disposed within the socket 8, whereby said fuse 17 will be held securely within the socket in a horizontal position, since obviously the fingers 11 and 16 respectively will exert sufficient pressure to urge the parallel end portions of their respective contact members 10 and 12 inwardly toward one another, whereby the ends of the fuse 17 will be maintained within their respective seats 18 and 19.

As is apparent, the bight portion 13 of the 190

contact member 12 provides a spring contact for the bottom of the body 5 of the plug.

From the foregoing it will be seen that the construction is exceedingly compact, that the plug consists of but comparatively few parts, and that the socket 18 being of sufficient diameter, one's finger may be inserted therein in order to secure a firm grip upon the fuse 17 when removing or replacing the fuse.

Even though I have herein shown and described the preferred embodiment of my invention, it is to be understood that the same is susceptible to changes fully comprehended by the spirit of the invention as herein described, and the scope of the appended claims.

Having thus described my invention, what I wish to claim is:

- 20 1. A fuse plug having a recessed cylindrical body, a metallic sleeve disposed about said body, said sleeve being screw threaded, a pair of spring contact members imbedded within said body, said contact members having one end thereof extending into the recess, one of said contact members having an intermediate portion thereof extending exteriorly of the body at a point remote from the recess, and the ends of said contact members within said recess being provided with oppositely disposed pockets, and a fuse in said recess, the ends of said fuse being received in the pockets of said contact members.
- 25 2. A fuse plug having a recessed body, a pair of contact members arranged in the body, said contact members respectively having one end thereof arranged in the recess of said body, means normally urging the said one end of said members inwardly toward one another, a fuse arranged in the recess of said body between said ends of said contact members, said ends of said contact members provided with pockets for receiving the ends of said fuse.
- 30 3. A fuse plug having a recessed body, a pair of contact members arranged in the body, said contact members respectively having one end thereof arranged in the recess of said body, means normally urging the said one end of said members inwardly toward one another, a fuse arranged in the recess of said body between said ends of said contact members, said ends of said contact members provided with pockets for receiving the ends of said fuse.
- 35 4. A fuse plug having a recessed body, a pair of contact members arranged in the body, said contact members respectively having one end thereof arranged in the recess of said body, means normally urging the said one end of said members inwardly toward one another, a fuse arranged in the recess of said body between said ends of said contact members, said ends of said contact members provided with pockets for receiving the ends of said fuse.
- 40 5. A fuse plug having a recessed body, a pair of contact members arranged in the body, said contact members respectively having one end thereof arranged in the recess of said body, means normally urging the said one end of said members inwardly toward one another, a fuse arranged in the recess of said body between said ends of said contact members, said ends of said contact members provided with pockets for receiving the ends of said fuse.
- 45 6. A fuse plug having a recessed body, a pair of contact members arranged in the body, said contact members respectively having one end thereof arranged in the recess of said body, means normally urging the said one end of said members inwardly toward one another, a fuse arranged in the recess of said body between said ends of said contact members, said ends of said contact members provided with pockets for receiving the ends of said fuse.

In testimony whereof I affix my signature.

EDWARD BERGER EKSTRAND.
